UNITED STATES PATENT OFFICE.

HAROLD F. ELY, OF BROOKLYN, NEW YORK.

WATER-TUBE BOILER.

937,782.

Specification of Letters Patent. Patented Oct. 26, 1909.

Application filed November 24, 1908. Serial No. 464,218.

To all whom it may concern:

Be it known that I, HAROLD F. ELY, a citizen of the United States, residing at Brooklyn, in the county of Kings and State of New York, have invented new and useful Improvements in Water-Tube Boilers, of which the following is a specification.

This invention relates to improvements in water tube boilers, the object of the invention being to provide a novel construction and arrangement of parts insuring strength, durability and economy of construction and operation, rapid and effective generation of steam, and ease of access to the parts for cleaning, repairs and replacement when occasion requires.

The invention consists of the features of construction, combination and arrangement of parts hereinafter fully described and claimed, reference being had to the accompanying drawing, showing a vertical longitudinal section of a boiler embodying the invention.

Referring to the drawing, 1 designates the boiler casing, which is preferably formed of a frame work of steel beams and walls of masonry of a refractory character or lined with refractory material, the front wall 2 being provided with the customary fire door or doors 3 and ash door or doors 4. The front wall may also be provided with suitable tube doors and at convenient points in the setting suitably closed openings may be provided to give access to the interior of the setting for cleaning or other purposes. I have not deemed it necessary to show these tube doors and openings, as they may be of any suitable construction and arrangement and form no part of the invention. The grate 5 is arranged in the lower front portion of the casing between the front wall and an upstanding bridge wall or abutment 6, and in rear of this bridge wall or abutment is another upstanding wall or abutment 7.

Suitably seated within and supported upon the front wall 2 at the upper front portion of the furnace casing is a horizontal transverse drum 8, and similarly arranged at the top and bottom of the rear of the casing are horizontal transverse drums 9 and 10, the drum 9 being arranged above and the drum 10 below the horizontal plane of the drum 8. The drums 8 and 10 are preferably of the same diameter, while the drum 9 is of larger diameter than said drums 8 and 10 and provided in practice with the

usual feed water inlet and steam outlet connections. (Not shown.) Each of these drums is formed in one of its heads with a manhole to give access thereto for cleaning and repairs, which manhole is closed by a suitable cover plate 11.

The drum 8 is connected with the drum 9 by an upper rearwardly and upwardly inclined bank of water tubes 12, and with the drum 10 by a downwardly and rearwardly inclined bank of water tubes 13, while the drum 10 is in turn connected with the drum 9 by a rear vertical bank of tubes 14. The tubes of each bank are disposed in parallel relation or substantially so, but their end portions are curved or bent at a proper radius to enter the drums radially and are expanded within their receiving openings in the drums so as to permit of their individual insertion and removal without interference with one another, thus providing for the ready and convenient removal of an old tube and its replacement with a new one.

The tubes 13 extend diagonally through the main chamber 15 of the casing and above the grate 5, and are subjected to the initial intense heat of the flames from the incandescent bed of fuel resting on the grate. In order to properly protect these tubes from the heat, as well as to provide for an effective spreading of the flames and circulation of the products of combustion to heat all the tubes, a baffle or partition 16 is provided between the grate and the portions of the lower tubes of the bank 13 between the drum 8 and bridge wall 6. This baffle 16 is preferably formed of fire-brick sections extending across the bottom of the bank and wholly or partially inclosing the lower tubes thereof for a suitable distance, as illustrated, to protect such lower tubes from the intense heat of the incandescent fuel, while forming a deflector to cause the flames and products of combustion to pass backwardly over the bridge wall 6 and through the space between the same and the lower rear portion of the baffle and into the space between said bridge wall 6 and the abutment 7.

Another shield or baffle 17, composed of fire-brick, tiles or other suitable material, overlies the upper tubes of the bank 13 from a point about midway of the length of the baffle 16 to the upper rear portion of the drum 10, said baffle inclining downwardly and rearwardly in parallel relation to the tubes, as shown. This baffle prevents the

flames and products of combustion from passing directly up between the tubes 13 into the upper central or upper rear portion of the chamber 15, and causes such flames and products of combustion to travel upwardly and forwardly between and around the tubes 13, and to issue at the point or passage 18 at the upper front portion of the chamber 15 and below the front ends of the tubes of the bank 12, which tubes 12 are then subjected to the heat of a large proportion of the products of combustion circulating within the said upper portion of the chamber.

The tubes 14 are arranged within a vertical flue or passage 19 which communicates at its outer end with an outlet flue 20, through which the products of combustion pass outward to the stack. This flue 19 is formed by the abutment 7, lower rear end of the baffle 17 and a vertical partition 21 of fire-brick or other suitable material, depending downwardly from the lower portion of the drum 9 between the upper ends of the sets of tubes 12 and 14 and terminating above the lower rear portion of the baffle or partition 17 to provide a passage 22, connecting the lower rear portion of the chamber 15 with the lower end of the flue 19. This partition 21, which extends across the furnace chamber, prevents the products of combustion from passing directly from the upper portion of the chamber 15 to the outlet flue 20, and causes the same to flow downwardly through the passage 22 into the flue 19 and to heat the drums 9 and 10 and tubes 14 before discharging through the outlet 20. By this means the lower tubes of the bank 13 will be protected from injury by the direct and intense heat of the bed of incandescent fuel on the grate, while causing the flames and products of combustion to circulate in such manner as to thoroughly heat the tubes of each bank, so that all of the available heat units of the flames and products will be utilized before the products discharge into the stack. The lower rear drum 10 is provided with a suitable outlet pipe 23, through which the mud and other substances accumulating therein may be drawn off and discharged.

From the foregoing description, the construction and mode of operation of my improved water tube boiler will be readily understood, and it will be seen that the construction and arrangement of the drums and flues is such as to provide for the circulation of the water in an effective manner, and for the rapid conversion of the same into

steam. This construction and arrangement of the parts also insures simplicity, inexpensiveness of erection and maintenance, and ready and convenient cleaning and repairs of the parts when occasion requires. By constructing the inclosing casing of a frame work of steel and walls of masonry, a light, strong and durable type of casing is provided.

Having thus fully described the invention, what is claimed as new is:—

A water tube boiler comprising a casing having a grate at the lower front portion thereof, and front and rear bridge walls forming a pocket or chamber in rear of the grate, a drum at the upper front portion of the casing, drums at the upper and lower rear portions of the casing, the lower rear drum being arranged between the rear wall of the casing and rear bridge wall, upper and lower inclined sets of water tubes connecting the front drum with the rear drums, a vertical set of water tubes connecting the rear drums, inclined partitions above and below the lower set of inclined tubes and extending respectively from the lower rear drum to a point in advance of the front bridge wall and from the front drum to a point in rear of the front bridge wall, said partitions being thus arranged to provide passages above said pocket and in communication with the upper front portion of the furnace chamber for the circulation of the flames and products of combustion from the grate over the front bridge wall, into said pocket and upwardly and forwardly between the lower set of tubes and partitions to the upper portion of the chamber, whereby the upper set of tubes between the front drum and upper rear drum will be heated, and a vertical transverse partition depending from the base of the upper rear drum between the adjacent ends of the banks of tubes connected therewith and terminating above the rear ends of the upper partition and lower inclined bank of tubes and forming with the rear wall of the casing a vertical flue or passage inclosing the vertical tubes and the lower rear drum and having an outlet at its upper end and an inlet between the lower end of said vertical partition and the rear end of said upper inclined partition.

In testimony whereof I affix my signature in presence of two witnesses.

HAROLD F. ELY.
